DESIGN FOR A COVER FOR AN ELECTRIC SWITCH BOX OR THE LIKE

Ralph A. Millermaster and Alex A. Writzmann,
Milwaukee, Wis., assignors to Cutler-Hammer,
Inc., Milwaukee, Wis., a corporation of Delaware

Application November 24, 1937, Serial No. 73,156

Term of patent 14 years

To all whom it may concern:

Be it known that we, Ralph A. Millermaster and Alex A. Writzmann, citizens of the United States and residents of Milwaukee, in the county of Milwaukee and State of Wisconsin, have invented a new, original, and ornamental Design for a Cover for an Electric Switch Box or the like, of which the following is a specification, reference being had to the accompanying drawing, forming part thereof.

Figure 1 is a front elevational view of a cover for an electric switch box, showing our new design, and

Fig. 2 is a sectional view on line 2—2 of Fig. 1.

We claim:

The ornamental design for a cover for an electric switch box or the like, substantially as shown.

RALPH A. MILLERMASTER.
ALEX A. WRITZMANN.
